Charles E. Wissner

Attorney

UNITED STATES PATENT OFFICE.

LESLIE D. NOBLE, OF DETROIT, MICHIGAN, ASSIGNOR TO NOBLE FOOT BALANCER CO., OF DETROIT, MICHIGAN, A CORPORATION OF MICHIGAN.

FOOT SUPPORT.

Application filed March 31, 1920. Serial No. 370,103.

To all whom it may concern:

Be it known that I, LESLIE D. NOBLE, a citizen of the United States, residing at Detroit, county of Wayne, State of Michigan, have invented a certain new and useful Improvement in Foot Supports, and declare the following to be a full, clear, and exact description of the same, such as will enable others skilled in the art to which it pertains to make and use the same, reference being had to the accompanying drawings, which form a part of this specification.

This invention relates to foot supports particularly for the use of people with fallen arches and the object of the invention is to provide a foot support which may be placed on the insole of the shoe and which is adapted to cause the foot to support, on the outer side thereof, the weight of the body. With this device the weight of the body is carried by the ball and heel of the foot and the outer edge of the sole thereby removing the weight and pressure from the arch of the foot so that the arch may return to its correct position and grow naturally in the correct form. An additional object of the invention is to provide, at the forward end of the device, a support for the metatarsus bones of the foot which automatically adjusts itself to support feet of different shapes thereby also tending to aid greatly in the correction of foot deformities. These objects and the several novel features of the invention are herein-after more fully described and claimed and the preferred form of the device, by which these objects are attained, is shown in the accompanying drawings in which—

Fig. 1 is a view of the device as positioned in a shoe, the shoe being indicated by dotted lines in the said figure.

Fig. 2 is a full size view of the under side of the device.

Fig. 3 is a section taken on line 3—3 of Fig. 2.

Fig. 4 is a section taken on line 4—4 of Fig. 2.

Fig. 5 is a section taken on line 5—5 of Fig. 2.

The foot support consists of a member 1 preferably made of leather and thicker at one edge than at the other as indicated in Fig. 5. As will be seen from Fig. 3 the leather is tapered so that it is quite thin at the forward end 2 and a protruding pad 3

is formed on the under side thereof as indicated in Figs. 2, 3 and 4. 55

As is shown in Fig. 5, the device is much thicker on the edge 4 than the edge 5 and is tapered throughout its width. When this device is positioned in the shoe the supporting surface 6 is much higher at the edge 4 than the edge 5 thereby causing the weight of the body to be supported on the edge of the sole adjacent the edge 5, the ball and heel of the foot supporting the weight at both 65 ends. By thus causing the weight to be supported on the outer edge and ball and heel of the foot, the arch naturally takes a position above the edge 4 thereby causing the arch of the foot to be normally positioned by 70 the position of the foot itself within the shoe, continuous use of the device strengthening the arch and tending to correct the deformities of the foot.

At the forward end and beneath the ball 75 of the foot is the pad 3 which tends to support the metatarsus bones of the foot, the leather at 2 and 7 being of sufficient thinness to conform to the shape of the foot about the ball and provide a support therefor. The 80 leather which is thin at 2 and 7 will be depressed to conform to the shape of the foot about the ball so that the foot is not only supported by the member 3 but also by the leather thereabout. This support of the 85 metatarsus bones also aids greatly in the strengthening of fallen arches and correcting the deformities of the foot.

The device is made up in two opposite forms, the one shown being made for the left 90 foot and one opposite to that shown being made for the right foot. In use the two devices are placed one in each right and left shoe as shown in Fig. 1 and in use the device will conform to the shape of the foot and 95 form a support therefor thereby doing away with arch supports which when once used must be continuously used.

From the foregoing description it becomes evident that the device, while of a very simple nature and of low manufacturing cost, 100 is of great utility and accomplishes the object desired.

Having thus briefly described my invention, its utility and mode of operation, what 105 I claim and desire to secure by Letters Patent of the United States is—

1. A foot support comprising a member

2
formed of a single piece of material shaped to fit within a boot or shoe and extending from the heel to a point forward of the metatarsal bones of the foot, the heel portion being tapered in transverse section, the material being made thin for the purpose of securing flexibility from a point at the rear of the metatarsal bones to the forward end of the support, there being an integral central pad at least equal in thickness to the thickest portion of the support on the under side of the support directly beneath the metatarsal bones.

2. A foot support comprising a leather member adapted to fit within a boot or shoe 15 extending forwardly from the heel and terminating beneath the metatarsal bones, and a pad provided on the under side of the forward portion of the said member and having a flat bearing surface, the leather about the 20 pad being reduced in thickness to form a yieldable support for the metatarsal bones unsupported directly by the pad.

In testimony whereof, I sign this specification.

LESLIE D. NOBLE.
